US0D1035238S

(12) **United States Design Patent** (10) Patent No.: **US D1,035,238 S**
(45) Date of Patent: ** Jul. 16, 2024

(54) **SHOE**

(71) Applicant: **Reebok International Limited**,
Altrincham (GB)

(72) Inventors: **Dustin Simone**, Boston, MA (US);
John Greenhalgh, Foxboro, MA (US);
Matthew Boudreau, North Attleboro,
MA (US)

(73) Assignee: **Reebok International Limited**,
Altrincham (GB)

(**) Term: **15 Years**

(21) Appl. No.: **29/782,915**

(22) Filed: **May 10, 2021**

Related U.S. Application Data

(63) Continuation of application No. 29/703,963, filed on Aug. 30, 2019, now Pat. No. Des. 920,646, which is a continuation of application No. 29/628,145, filed on Dec. 1, 2017, now Pat. No. Des. 862,869.

CLAIM

The ornamental design for a shoe, as shown and described.

DESCRIPTION

FIG. 1 is a bottom front perspective view of a shoe showing the claimed design;

FIG. 2 is a bottom rear perspective view thereof;

FIG. 3 is a left side view thereof;

FIG. 4 is a right side view thereof; and,

FIG. 5 is a bottom view thereof.

The dashed broken lines in the figures show portions of the shoe that form no part of the claimed design.

The dot-dash broken lines in the figures show boundaries that form no part of the claimed design.

1 Claim, 5 Drawing Sheets
